COMBINED DISPLAY STAND AND FILING RACK

Harry Goldman, Detroit, Mich.

Application November 30, 1937, Serial No. 177,355

2 Claims. (Cl. 211—134)

This invention relates to improvements in combined display stands and filing racks. It is to a retail merchant's advantage to display goods upon his counter as it stimulates sales, but the counter space available for this purpose is obviously limited. It is also necessary for him to utilize some space for the storage of bags of various sizes which he constantly uses. It is therefore an object of this invention to provide a combined display stand and filing rack having deep side walls which afford a firm footing for the device, to employ a transverse partition extending between the side walls intermediately of their length, and to provide a display stand on one side 10 of the partition and a filing rack extending from the other.

Another object of the invention is to provide a combined display stand and filing rack which is compact, relatively cheap and simple to manufacture, and wherein practically all the space is utilized.

A further object of the invention is to provide a combined display stand and filing rack in one preferred embodiment of which the shelves of 25 the stand are mounted for pivotal movement so that while they extend forwardly beyond the sides of the device when the latter is in use they may be withdrawn into the stand for shipment thereby protecting them against possible damage 30 in transit.

Yet another object of the invention is to provide such a combined display stand and filing rack wherein the transverse partition is downwardly inclined towards the display stand side 35 of the device thereby affording support for the open lids of boxes of merchandise displayed upon the shelves of the stand. Moreover the inclined partition also affords support for the pivoted shelves when the latter are turned upward to 40 their limit of travel.

Having thus briefly stated some of the major objects and advantages of the invention, I will now proceed to describe preferred embodiments thereof with the aid of the accompanying drawing in which

Figure 1 illustrates a front elevation of the invention.

Figure 2 is a section on the line 2—2 of Figure 1.

Figure 3 is a rear elevation.

Figure 4 is a side elevation of a slightly modified form of construction wherein the shelves are permanently secured in a horizontal position, and

Figure 5 is a fragmentary view showing a partial front elevation of Figure 4.

Referring to the drawing, 1 and 2 designate two spaced, parallel walls one lateral margin of each of which is downwardly and outwardly inclined while their opposite lateral margins are substantially vertical. Moreover each pair of lateral margins is in horizontal alignment. A transverse partition 3 connects the walls 1 and 2 intermediately of their length and is disposed substantially parallel with the inclined margins of the walls 1 and 2.

Mounted between the walls 1 and 2 and projecting outwardly beyond their inclined lateral margin are a plurality of trays, 4, 4a or 4b. In Figures 1 and 2 trays 4 and 4a are shown mounted for pivotal movement. The upper tray 4 is 10 pivotally supported by pins 5 extending from the walls 1 and 2, and is held in the horizontal position shown by stops 6 also projecting from the said walls. The tray 4 is thus normally held in a horizontal position to receive a box of merchandise A with its lid A1 resting against the inclined partition 3. When it is desired to ship the device the tray 4 is swung upwardly about the pins 5 until its outer margin lies in proximity to the partition 3, when the tray is protected by the side walls 1 and 2. The tray may also be moved into its upward position to facilitate the 15 cleaning and dusting of the device.

The lower tray 4a is also supported for pivotal movement. In this case inner pivot pins 5a are employed, and the shelf is retained in its horizontal position by outer removable pins 7. When the latter are removed obviously the tray 4a may be turned pivotally about the inner pins 5a into the position indicated at 4aa.

In the modified arrangement shown in Figures 4 and 5 the sides of the tray 4b adjacent the walls 1 and 2 are secured to the latter as by welding so that in this form of construction the trays remain in one fixed position.

Mounted horizontally between the upper extremities of the walls 1 and 2 is a top tray 4c the rear margin of which is upwardly flexed to form a vertical rest 4d. Formed in the latter and extending rearwardly therefrom are means for supporting an advertising card B. The supporting means herein shown consists of two spaced, rearwardly disposed, and upwardly projecting fingers 8 formed integral with the rest 4d.

Mounted between the walls 1 and 2, extending 50 from the partition 3, and terminating substantially flush with the vertical margins of the walls are a plurality of shelves 9, 9a, 9b and 9c which are preferably upwardly and outwardly inclined. These shelves are of different lengths and are 55

primarily intended to hold paper bags of different sizes. The lateral margins of the shelves are welded or otherwise suitably secured to the walls 1 and 2. The upper shelf 9 in the present instance consists of a flat plate, whereas the lower shelves 9a, 9b and 9c have upwardly flexed inner extremities. The inner extremity of the shelf 9 is suitably secured to the partition 3, as also is the upwardly flexed extremity of the shelf 9a, whereas the upwardly flexed extremities of the shelves 9b and 9c are secured to the undersides of the shelves 9a and 9b respectively. Formed integral with the lower shelf 9c is a downwardly extending apron 9b which extends the full distance between the walls 1 and 2 and terminates substantially flush with the bottom of the latter. This apron both prevents articles sliding accidentally beneath the device, and also strengthens the structure. In order to provide separate pockets 10 for each size of bag commonly used the shelves 9a, 9b and 9c are each divided by partitions 11 which extend vertically between each pair of adjacent shelves. 12 denote inserted pocket ends of angle-shape which may either be secured to and project from the upper or lower faces of the shelves.

From the foregoing it will be readily seen that I have provided a simple and efficient device for accomplishing two necessary purposes, and in so combining them I provide a device of sufficient width to rest firmly upon a counter without taking up unnecessary space.

In order to permit changes as to height of the shelves 4 and 4a the side walls 1 and 2 may be provided with aligned openings as shown at 5x and 1x to receive the pins 5a and 7 respectively.

While in the foregoing the preferred embodiments of the invention have been described and shown it is understood that the construction is susceptible to such further alterations and modifications as fall within the scope of the appended claims.

What I claim is:

1. A display stand comprising two vertical walls

spaced from one another, an abruptly inclined transverse partition having its opposite ends secured to and between said walls intermediately of the depth of the latter, a fixed top tray supported upon said walls and extending over said transverse partition, other trays pivoted about horizontal axes between said walls, each pivoted tray being adapted to be turned upwardly to rest against the partition or to be turned to a horizontal position, stops carried by the walls to support the pivoted trays in their horizontal positions, said trays being of such size and being so positioned that when horizontal they extend forwardly beyond the front margins of said walls and when upturned they lie entirely rearwardly of said front margins, the partition being adapted to support the upturned covers of boxes resting upon the pivoted trays when the latter are horizontal.

2. A display stand comprising two vertical walls spaced from one another, a transverse upwardly and rearwardly inclined partition having its opposite ends secured to and between walls intermediately of the depth of the latter, a fixed top tray supported along opposite ends upon said walls substantially throughout their depth, other trays pivoted about horizontal axes between said walls, each pivoted tray being adapted to be turned upwardly to rest against the partition or to be downturned to a horizontal position, stops carried by the walls to support the pivoted trays in their downturned positions, said pivoted trays being vertically so spaced that the upper margin of one upturned tray lies beneath the lower margin of the next tray above it, and said trays being so positioned and of such size that when horizontal they extend forwardly beyond the front margins of the walls and when upturned they lie entirely rearwardly of said front margins, the partition being adapted to support the upturned covers of boxes resting upon the pivoted trays when the latter are horizontal.

HARRY GOLDMAN.
